UNITED STATES PATENT OFFICE.

RAYMOND L. CLARK, OF ROCHESTER, NEW YORK.

RAIL-FASTENING DEVICE.

1,085,797.

Specification of Letters Patent. Patented Feb. 3, 1914.

Application filed August 27, 1913. Serial No. 786,973.

To all whom it may concern:

Be it known that I, RAYMOND L. CLARK, a citizen of the United States, and resident of Rochester, in the county of Monroe and 5 State of New York, have invented certain new and useful Improvements in Rail-Fastening Devices, of which the following is a specification.

This invention relates to rail-fastening devices of the type in which the base of the rail is engaged by means of a clamping-member secured in place by a bolt, particularly where such clamping-member is employed in connection with a chair or pedestal 15 adapted to be mounted on or embedded in a tie.

One object of the invention is to protect the screw-bolt, by which the clamping-member is secured in place, against rusting due 20 to the access of moisture. To this end I provide the pedestal with an upward projection which is received in a recess in the clamping-member, the projection and the recess surrounding the bolt and acting to prevent water from flowing freely in between the adjacent surfaces of the pedestal and the clamping-member. As a further protection for the 25 same purpose I preferably employ a watertight gasket between the pedestal and the clamping-member, and also a cover which closes the latter above the head of the bolt.

Another object of the invention is to provide effectually against turning of the clamping-member about the axis of the bolt, and 30 for this purpose I utilize the projection and recess above referred to, by making them of non-circular form, so that they prevent relative rotation of the parts.

A third object of the invention is to provide simple and effective means for locking the head or the nut of the screw-bolt against rotation and loosening. To this end I provide the clamping-member with a non-circular recess to receive the head or nut of the 45 bolt, and into this recess I introduce a locking-member, which lies loosely between the wall of the recess and one or more of the flat sides of the bolt-head or nut. This locking-member is preferably retained in place 50 by the cover hereinbefore referred to, by which moisture is excluded from the head of the bolt.

In the drawings Figure 1 is a vertical section, transverse to the rail; Fig. 2 is a plan-view of the parts shown in Fig. 1, partially broken away on the lines 2-2 and 2^a-2^a of

Fig. 1; and Fig. 3 is a longitudinal section of a railway-tie provided with the fastening devices of the present invention showing both rails in place.

60

The main elements of the rail-fastener comprise a heavy pedestal 5, which is preferably a casting, and removable caps 6 which are adapted to engage the flange or base of the rail. The pedestal 5 is adapted to be 65 embedded in a tie 7 (see Fig. 3) of concrete or similar material. A flange or ledge 8 extends completely around the pedestal, and projects horizontally therefrom. The concrete completely covers this flange, the upper 70 surface of the tie being made approximately flush with the upper surface of the pedestal. Means are also provided for maintaining the proper distance between the pedestals of both rails. The means shown in the drawings comprise a rod 9 that extends through 75 holes 10 in each pedestal, and is provided with collars 11 and nuts 12 to engage the ends of the pedestal.

The rail 13 is so placed upon the pedestal 80 5 as to lie midway between its ends. Adjacent to each end is an upwardly-projecting lug 14 of substantially rectangular form, and the removable cap 6 has a socket 15 in its lower side which is approximately of the 85 same size and shape as said lug. At one side of the cap 6 is a lug 16 which overlies, and conforms to, the base of the rail, being sufficiently long to extend well up toward the web of the latter. The cap 6 has a central, 90 vertical perforation, through which a screw-bolt 17 is passed and screwed into the pedestal 5, the head of the bolt lying within a depression 18 in the top of the cap. Because of the rectangular form of the lugs 14 and 95 their corresponding sockets 15 the caps cannot turn laterally, and accordingly must remain always in engagement with the rail. A further useful function performed by the lugs 14 resides in the exclusion of moisture 100 from the threaded openings in the pedestal in which the bolts are seated. The projection of the lugs above the general surface of the pedestal tends to prevent water from flowing along this surface and into engagement with the bolts. As a further protection against such access of water, however, I preferably employ a gasket 19 of leather, fiber or similar compressible material laid upon the lug 14 before setting the cap 6 in 110 place. This gasket is of such thickness as to be considerably compressed when the bolt 17

is drawn tight, thus preventing entrance of water beneath the cap which might reach the threaded portion of the bolt and rust it.

To prevent water from reaching the bolt 5 17 from above, the caps 6 are provided with sliding covers 20 which engage beads 21 on the caps. These covers are preferably made of non-rusting sheet-metal, and may be readily removed so that the heads of the 10 bolts may be reached with a socket-wrench of special form.

A novel form of lock is also a valuable feature of the invention for the purpose of preventing the bolts 17 from becoming 15 loosened. This lock consists of a flat L-shaped piece of metal 22 (Fig. 2) which is loosely seated between the head of the bolt on two sides, and the adjacent sides of the 20 socket 18. With this L-shaped piece in the position shown it is impossible for the bolt to turn. On sliding off the cover 20 the piece 22 may be lifted out, whereupon the bolt 17 can be removed.

I claim:—

25 1. A rail-fastening device comprising a pedestal adapted to be embedded in concrete or similar material, and to support a rail between its ends; a removable cap for each end, each cap having a lug adapted 30 to overlie the base of the rail, a central, vertical perforation for a clamping bolt, and a socket in its top to receive the head of the bolt; a bolt for clamping each cap to the pedestal; and a removable cover for 35 each cap; substantially as shown and described.

40 2. A rail-fastening device comprising a pedestal adapted to be embedded in concrete or similar material, and to support a rail between its ends, and having an upwardly-extending lug of non-circular form 45 at each end; a removable cap for each end, each cap having a socket in its lower side adapted to receive one of said lugs and approximating the lug in size and shape, a lug adapted to overlie the base of the rail, a central, vertical perforation for a clamping-bolt, and a depression in its top to receive the head of the bolt; a bolt for clamping 50 each cap to the pedestal; and a removable cover for each cap; substantially as shown and described.

55 3. A rail-fastening device comprising a pedestal adapted to be embedded in concrete or similar material, and to support a rail between its ends; a removable cap for each end, each cap having a lug adapted to overlie the base of the rail, a central, vertical perforation for a clamping bolt, and a rec-

tangular socket in its top to receive the head 60 of the bolt; a bolt for clamping each cap to the pedestal; an L-shaped nut lock adapted to enter the socket in the top of the cap, and lie between the head of the bolt and the adjacent walls of the socket; and a removable cover for each cap; substantially as shown and described.

4. A rail-fastening device comprising a cap provided with a lateral lug to overlie the base of a rail, a vertical perforation to 70 receive a bolt, and a socket, in its upper surface, to receive the head of the bolt; and a removable cover for closing said socket.

5. A rail-fastening device comprising a cap provided with a lateral lug to overlie 75 the base of a rail, a vertical perforation to receive a bolt, a socket, in its upper surface, to receive the head of the bolt, and a non-circular socket, in its lower surface, surrounding said perforation.

80 6. In a rail-fastening device, the combination of a pedestal provided with a screw-threaded bolt-receiving opening and an integral upward projection surrounding said opening; a cap provided with a lateral lug, 85 to overlie the base of a rail, a recess in its lower surface, to receive said upward projection, and a bolt-receiving perforation alining with said opening; and a removable cover, upon said cap, for excluding moisture 90 from the head of the bolt.

7. In a rail-fastening device, the combination of a pedestal provided with a screw-threaded bolt-receiving opening and an integral upward projection surrounding said 95 opening; a cap provided with a lateral lug, to overlie the base of a rail, a recess in its lower surface, to receive said upward projection, and a bolt-receiving perforation alining with said opening; a removable 100 cover upon said cap, for excluding moisture from the head of the bolt; and a gasket interposed between the top of said projection and the recessed surface of the cap.

8. In a rail-fastening device, the combination, with a screw-bolt, of a cap provided with a rail-engaging member, a perforation to receive the shank of the bolt, and a non-circular recess to receive the head of the bolt; a locking-member loosely seated between, 110 and conforming to, the head of the bolt and an adjacent non-circular surface of said recess; and a removable cover for closing said recess.
